ELECTRIC DISCHARGE DEVICE

Stephan P. Sashoff, Swissvale, Pa., assignor to
Westinghouse Electric & Manufacturing Company, a corporation of Pennsylvania

Application December 4, 1931, Serial No. 578,904

9 Claims. (Cl. 250—27)

My invention relates to electric discharge devices and has particular relation to gaseous electric discharge devices of a type having symmetric electrical properties.

5 It is an object of my invention to provide a gaseous electric discharge device having the property of symmetric conductivity and capable of accurate control.

Another object of my invention is to provide 10 for a gaseous electric discharge device of the type capable of symmetric conductivity, a control electrode of such geometric structure that it shall completely prevent the transmission of a current in the device unless it is given the proper 15 potential relative to the principal electrodes thereof.

Still another object of my invention is to provide 20 an electric discharge device having the property of symmetric conductivity and capable of conducting substantially identical wave forms in both directions.

A further object of my invention is to provide 25 an electric discharge device, of the type having the property of symmetric conductivity and incorporating a control electrode, that shall yield a substantially symmetric electrical output.

More concisely stated, it is an object of my 30 invention to provide an electric discharge device incorporating a control electrode and having the property of symmetric electrical conductivity, such that the control electrode shall always regulate the activity of the device and the current transmitted by the device shall have the proper symmetric properties.

35 In experimenting with gaseous electric discharge devices of the type having the property of symmetric conductivity, I have found that unless the elements of the principal electrodes of a gaseous device are substantially completely 40 shielded from each other by the control electrode, the device has a tendency to become energized by reason of the fact that an ionization current flows between the elements of the principal electrodes that are exposed to each other. 45 I have therefore, provided an electric discharge device comprising a plurality of principal emitting electrodes preferably of the hot-cathode type, and a control electrode of such structure that it completely shields the principal electrodes from each other.

50 The principal electrodes normally comprise a plurality of filaments suitably supported on a plurality of conducting rods through which the heating energy is fed to the filaments. The control electrode is an open structure preferably of

cylindrical form. The base of the cylinder is disposed between the electrodes, while the walls of the cylinder enclose one of the electrodes and its supporting structure. By reason of the shielding provided by the structure of the control electrode, emission is prevented through the gaseous medium between the elements of the supporting structure of the principal electrodes. 5

In experimenting with the tube of the structure described hereinabove, I have found that 10 for many purposes it is completely suitable. However, when it becomes necessary that the electric discharge device shall be utilized to transmit symmetric disturbances in such manner that substantially complete symmetry shall be pre- 15 served between the half waves transmitted in each direction, I have found that the structure described above must be, to a certain extent, modified. For complete symmetric conductivity, the mechanical structure of the electric discharge 20 device should be as nearly symmetric as possible. In such a case, the control electrode should preferably bear the same relation to one principal electrode as it does to the other.

In a modification of my device particularly 25 adaptable to symmetric conductivity, I have found that the control electrode should preferably be in the form of a hollow cylinder divided into two sections by a central partition. The cylinder is disposed with its walls adjacent and 30 parallel to the supporting structure of the principal electrodes, and with the partition parallel to the emitting filaments of the electrodes.

It is moreover well to keep in mind that when 35 complete symmetric conductivity is desired, the input and the output circuits associated with the device should be as nearly symmetric as possible.

The novel features that I consider characteristic of my invention are set forth with particularity in the appended claims. The invention 40 itself, however, both as to its organization and its method of operation, together with additional objects and advantages thereof, will best be understood from the following description of specific embodiments when read in connection with 45 the accompanying drawing, in which:

Figure 1 is a view in section of an embodiment of my invention; and

Fig. 2 is a view, partly diagrammatic and partly 50 in section, showing a modification of my invention which is particularly applicable to a system in which complete symmetry in conductivity is essential.

The apparatus shown in Fig. 1 comprises a container 55 preferably composed of non-conducting

material such as glass, and equipped with a plurality of re-entrant stems 3 and 5 and a plurality of presses 7 and 9, integral with the stems. A plurality of leads 11 and 13 of comparatively heavy structure project through each of the presses 7 and 9 and are so welded thereto that the leakage of air into the container 1 is prevented. Filaments 15 and 17 capable of electron emission, which may be of the thoriated type or of the oxide-coated type, are suitably secured to the terminals of each pair of leads 11 and 13 that project through the presses 7 and 9. The filaments 15 and 17 may be suitably heated by current which is supplied through the leads 11 and 13 from a source of power (not shown).

The control electrode 19 comprises a cylindrical open structure disposed about one filament 17 and its associated leads 13 and suitably supported by a plurality of rods 21 which are secured to a metallic collar 23. The collar 23 is, in turn, mounted on the stem 5 and is secured by a screw 27, which passes through openings in a plurality of lips 29 extending from the terminals of the collar, and engages a nut 31. The electromotive force that is applied to the control electrode 19 is brought in through a lead 33 which is sealed to the press 5, and to one terminal 35 to which a flexible wire 37 soldered to the collar 23, is secured.

The envelope 1 in which the electrodes are disposed may be suitably evacuated before it is sealed off. It is well to remember that my invention is applied in particular, to tubes in which a quantity of gas is disposed within the envelope. As is well known, the pressure of the gas within the envelope may vary from a few microns to several centimeters of mercury. The characteristic of the device is, of course, dependent on the pressure of the gas within the envelope and on the character of the gas. However, it is apparent that as long as sufficient gas for ionization is present within the container, spurious conductivity will take place between the elements of the principal electrodes 15 and 17 unless they are properly shielded from each other by the control electrode 19.

While my invention has particular applicability to gaseous electric discharge devices, it should be kept in mind that in certain connections it may be applied even to high vacuum devices. Insofar as my invention does apply to high vacuum devices, its scope should be extended to include such devices.

The apparatus of the type shown in Fig. 2 is in many respects similar to the apparatus shown in Fig. 1. However, the device shown in this view is more symmetric in its structure than the device shown in Fig. 1. The principal element of symmetry in the device is the control electrode 39 which comprises an attenuated open-end cylinder equipped with a central partition 41. The walls of the cylinder 39 are disposed adjacent to the supports 11 and 13 of the filaments 15 and 17 and the partition 41 is disposed substantially midway between the two filaments. The cylindrical control electrode 39 is supported from a collar 23, as is the control electrode 19 of apparatus of the type shown in Fig. 1, and the electromotive force is supplied thereto through a lead 33 sealed to the press 9 and through a wire 37 soldered to the collar 23 and secured to the internal end 35 of the lead 33.

The energy for heating the filaments 15 and 17 is applied to the leads 11 and 13 through a plurality of transformers 43 and 45 of similar

electrical characteristic. The central taps 47 and 49 of the secondaries 51 and 53 of the transformers 43 and 45 whereby the power is applied for heating the filaments 15 and 17 are connected to each other through a suitable alternating power supply source (not shown) and through the load 55 which the system is to feed. A plurality of impedances 57 and 59 of substantially similar characteristics are connected across the alternating source.

The control electrode 39 is connected to the junction of the impedances 57 and 59 preferably through a suitable biasing battery 61 and through the secondaries 63 and 65 of a plurality of transformers 67 and 69 whereby the potentials necessary for the control of the electric discharge device are applied to the control electrode 39. One of the transformers may be utilized for applying the suitable controlling potential for the combination of one principal electrode and the control electrode, and the other transformer may be utilized for the control of the other combination of principal electrode and control electrode.

It is to be noted that for certain purposes a single transformer may be utilized for control. However, if two transformers are utilized the electromotive forces impressed for controlling purposes should not be of the sinusoidal type, for in such a case a combined effect produced by the two transformers will be a new effect such as would be produced by a single transformer. If the electric discharge device is utilized for controlling the magnitude of current through the load, the electro-motive forces applied to the controlling transformers 67 and 69 are such that the device conducts current from a predetermined point in each half wave of voltage applied to the principal electrodes.

In such a case the secondaries 63 and 65 of the controlling transformers 67 and 69, respectively, may have induced in them starting impulses of suitable character and at suitable intervals to yield the necessary power. The current transmitted by the tube will, in such a case, be controlled by the point in the half wave of the voltage applied to the principal electrodes 15 and 17 of the tube at which the impulse is applied to the control electrode 39. The point may be shifted by some phase-shifting device which may be suitably associated with the controlling transformers.

The controlling transformers may be utilized to start and stop the current transmitted by the principal electrodes 15 and 17 in suitable manner. Thus, one transformer may provide a potential to the control electrode 39 for blocking the discharge in the tube while the other may be utilized for applying a potential to the control electrode 39 to start a discharge in the tube.

Although I have shown and described certain specific embodiments of my invention, I am fully aware that many modifications thereof are possible. My invention, therefore, is not to be restricted except insofar as is necessitated by the prior art and by the spirit of the appended claims.

I claim as my invention:

- An electric discharge device comprising a plurality of excitable electrodes forming the terminals of a discharge path, means for supporting said electrodes and a perforated electrode completely enclosing one of said excitable electrodes and said supporting means associated therewith and an electrical network having said excitable electrodes as the terminals thereof.

2. A gaseous electric discharge device comprising a container a plurality of excitable electrodes forming the terminals of a discharge path disposed within said container, means for supplying power to said electrodes and a perforated electrode completely enclosing one of said excitable electrodes and the elements of said power supply means associated therewith that are disposed within said container and an electrical network 10 having said excitable electrodes as the terminals thereof.

3. A gaseous electric discharge device including a plurality of electrodes to be heated and to emit electrical charges when in heated condition and 15 to form terminals of a discharge path, means for supporting said electrodes and a control electrode comprising an open structure completely enclosing one of said electrodes and said supporting means associated therewith and an electrical 20 network having said electrodes to be heated as the terminals thereof.

4. A gaseous electric discharge device including a container, a plurality of electrodes to be heated and to emit electrical charges when in heated 25 condition and to form the terminals of a discharge path, disposed within said container, means cooperating with said electrodes to supply the energy necessary for heating them and a control electrode comprising an open structure completely 30 enclosing one of said electrodes and the elements of said energy supply means associated therewith that are disposed within said container and an electrical network having said electrodes to be heated as the terminals thereof.

5. In a gaseous conductor having electrical symmetry of the type including a container having an ionizable medium enclosed therein, a plurality of emitters of electrical charges to ionize said medium, said emitters being disposed to alternately receive charges of opposite polarity, 35 means for supplying power to said emitters and a control electrode comprising an open structure enclosing said emitters and the elements of said

power supply means associated with said emitters that are disposed within said container.

6. A three-electrode electric discharge device comprising a discharge path, two incandescent main electrodes forming the terminals of the said discharge path and a control electrode extending across the discharge space between the two main electrodes. 5

7. An electric discharge device comprising a discharge path, a plurality of substantially similar main electrodes, means for maintaining both said electrodes in a state in which they emit electrical charges even when they are at the same electrical potential, said main electrodes forming the terminals of the said discharge path, and a control 15 electrode extending across the discharge path between said main electrodes, said main electrodes being symmetrical with respect to said control electrode.

8. In combination, an electric discharge device 20 comprising a discharge path, a plurality of electrodes adapted to emit electrical charges and of substantially similar structure and to form the terminals of the said discharge path and a control electrode intersecting substantially all of the 25 paths of said charges from one of said electrodes to another and a network having electrical symmetry similarly associated with each of said emitting electrodes, the electrical central elements of said network being connected with said control 30 electrode.

9. An electrical discharge device comprising a container, a discharge path in said container, a plurality of substantially similar main electrodes disposed in said container and forming the terminals of the said discharge path, means for maintaining both said electrodes in a state in which they emit electrical charges even when they are at the same electrical potential, a single control electrode intersecting substantially all of the 35 paths of said electrical charges from one main electrode to another main electrode. 40
